Primary Examiner — April Rivas

(57) CLAIM

The ornamental design for a cosmetic case, as shown and described.

DESCRIPTION

FIG. 1 is a front, left and top perspective view of a cosmetic case showing my new design;

FIG. 2 is a rear, right and bottom perspective view thereof; FIG. 3 is another front, left and top perspective view thereof, showing the cosmetic case in a closed configuration;

FIG. 4 is a front view thereof;

FIG. 5 is a rear view thereof;

FIG. 6 is a right view thereof;

FIG. 7 is a left view thereof;

FIG. 8 is a top view thereof;

FIG. 9 is a bottom view thereof;

FIG. 10 is an enlarged view of a portion labeled as 10 on FIG. 1;

FIG. 11 is an enlarged view of a portion labeled as 11 on FIG. 1;

FIG. 12 is an enlarged view of a portion labeled as 12 on FIG. 2;

FIG. 13 is an enlarged view of a portion labeled as 13 on FIG. 2; and,

FIG. 14 is an enlarged view of a portion labeled as 14 on FIG. 3.

The long dash-short dash broken lines depict enlargement boundaries that form no part of the claim. The evenly broken lines illustrate portions of the article that form no part of the claimed design.

1 Claim, 14 Drawing Sheets
